UNITED STATES PATENT OFFICE.

SAMUEL H. BOYLAN, OF DENVER, COLORADO.

HEAD-MOTION FOR CONCENTRATING-TABLES.

No. 901,585.

Specification of Letters Patent.

Patented Oct. 20, 1908.

Application filed May 13, 1907, Serial No. 373,403. Renewed March 7, 1908. Serial No. 419,770.

To all whom it may concern:

Be it known that I, SAMUEL H. BOYLAN, a citizen of the United States, residing in the city and county of Denver and State of Colorado, have invented certain new and useful Improvements in Head-Motions for Concentrating-Tables; and I do declare the following to be a full, clear, and exact description of the invention, such as will enable others skilled in the art to which it 10 pertains to make and use the same, reference being had to the accompanying drawings, and to the letters and figures of reference marked thereon, which form a part of this 15 specification.

My invention relates to improvements in mechanism adapted to impart a peculiar form of reciprocating movement to concentrators or other apparatus requiring such 20 action.

The invention is more especially adapted for use with concentrating tables where great accuracy of adjustment is required in order to get the proper character and length of 25 stroke, for separating metal values from the gangue.

The object of my present invention is to provide an improved mechanism of this character whereby the requisite accuracy of adjustment may be obtained both for the purpose of regulating the character or speed of the stroke in both directions, as well as for regulating the length thereof, all of which 30 will be fully understood by reference to the accompanying drawing in which is illustrated an embodiment thereof.

In this drawing, Figure 1 is a side elevation of my improved head motion shown in connection with a concentrating apparatus 40 which is partly broken away. Fig. 2 is a vertical longitudinal section taken through the mechanism. The plane of this section is indicated by the line 2—2 Fig. 3. Fig. 3 is a top plan view of my improved head motion without showing the concentrating table. Fig. 4 shows a number of blocks used for regulating the vertical adjustment of the outer extremity of one of the toggle members. Figs. 5 and 6 are side and top plan 45 views, respectively of the intermediate frame member. Figs. 7 and 8 are front and side views respectively, of the lever or rocker arm. Fig. 9 is a cross section taken on the line 9—9 Fig. 2.

50 The same reference characters indicate the same parts in all the views.

Let the numeral 5 designate a suitable base upon which are mounted vertically disposed side plates 6 having laterally projecting horizontal lugs 7 secured to the base by cap screws 8. Between these side plates 6, is located a bed plate 9 provided with longitudinal ribs 10 and a rearwardly located, upwardly projecting part 12. The side members 6 of the frame are connected with the 60 said bed plate in any suitable manner. The three members may be said to constitute the frame work upon which the operating parts of the mechanism are mounted. Projecting outwardly from each frame member 6, are 65 journal boxes 13 each of which is provided with a movable member 14 held in suitable relation with the journals of the crank shaft 15 by means of bolts 16 threaded in parts 17 of the journal boxes. The shaft 15 is provided with a crank centrally located between the side members of the frame and with which is connected a hanger 18. A part of the bearing for the crank is formed in the body of the hanger, while an upper box 80 member 19 is connected with the lower bearing by means of bolts 20. The lower part of this hanger is equipped with bearing blocks 21 which are engaged by the inner extremities of two toggle members 22 and 23. The outer extremity of the toggle member 23, engages a bearing 24 located in a block 25 adjustably mounted in a holder 26 by means of a screw 27. This holder 26 is held in place by means of cap screws 29 horizontally disposed, and passed through the side members 6 of the frame and also through the upwardly projecting angle parts 30 of the upwardly projecting part 12 of the bed plate. 90

The forward extremity of the toggle member 22, is seated in a block 31 carried by a lever 32 fulcrumed on trunnions 33. The block 31 is carried by the lower arm of this lever, while the upper arm of the lever carries a pin 34 engaged by a bearing composed of members 35 and 36 connected by bolts 37. With the member 35 is connected a rod 38 whose forward extremity is connected with a yoke 39 by means of nuts 40 and 41. This 100 yoke is in turn connected with a U-shaped member 42 by means of cap screws 43 which are threaded in the member 39, and engage vertically disposed grooves 44 formed in the sides of the member 42. This member 42 105 is connected with the concentrating table by means of a rod 45. 110

The trunnions 33 of the lever or rocker arm 32, engage seats 46 formed in the side frame member 6 and are also engaged by bearing blocks 47 grooved at the top and bottom to engage retaining plates 48 formed integral with the side members 6 to prevent lateral displacement. These blocks are also held in place from in front by means of keys 49. The keys 49 are wedge-shaped and when 10 properly adjusted vertically, are held in place by cap screws D engaging threaded openings formed in the frame member 6. The lower arm of the lever 32 is notched on its front side as shown at 50 to engage a 15 pointed projection 51 formed on a plate 52 provided with a socket 53 which receives one extremity of a coil spring 54, whose opposite extremity engages a seat 55 formed in the central part of a transverse bar 56 20 whose opposite extremities are connected by means of rods 57, with the respective side frame members 6. These members 6 are provided with exteriorly located vertically disposed ribs 58 through which the rods 57 25 pass, the said rods being held in place by means of nuts 59, which may be utilized to regulate the tension of the spring 54.

The pin 34 is vertically adjustable in an elongated opening 60 formed in the upper 30 arm of the lever 32. By the vertical adjustment of this pin and the corresponding vertical adjustment of the yoke 39 on the member 42, the length of stroke imparted to the concentrator 61 may be regulated at will.

35 By forming a number of notches 50 in the lower arm of the lever 32, it becomes practicable to use springs of different character. If the projection 51 engages the uppermost notch 50, comparatively little compression is 40 given to the spring. This adjustment is made when a strong or stiff spring is employed. When a spring of less strength and usually of greater length is used, the projection engages a lower notch whereby greater compression is given. This is an important feature in a device of this character.

The vertical adjustment of the outer or forward extremity of the toggle member 22, is effected by using a number of bearing blocks 31, having their recesses 31^A formed 50 at different elevations. This is equivalent to the vertical adjustment of a single bearing block. My improved lever, however, is so constructed that an adjusting bolt manipulated from the top cannot be as conveniently employed. For this reason I resort to the construction just explained. All the bearing blocks heretofore described, are provided with recesses B adapted to hold oil or other 60 lubricant which is allowed to flow to the engaging toggle member extremities.

From the foregoing description the use and operation of my improved mechanism will be readily understood. Assuming that 65 the parts are assembled as shown in the

drawing, as the crank shaft is rotated, the crank is given a short stroke whereby a vertical reciprocation is imparted to the hanger 18. This movement operates the toggle members. When the crank lifts the hanger, the lower arm of the lever 32 is thrust forward compressing the spring 54, while the upper arm of the said lever is moved rearwardly throwing the concentrating table or other device to be vibrated suddenly rearwardly. As 75 the crank moves the hanger downwardly, the reverse action occurs, that is to say the spring 54 acting on the lower arm of the lever 32 through the medium of the projection 51, throws the said arm rearwardly, and imparts 80 a forward movement to the upper arm of the same lever, thus giving the forward vibratory stroke to the concentrator. It is important that the action of the spring be utilized to give the forward stroke to the concentrator 85 since its action is slower than the action imparted by the toggle members; and from the nature of the concentrator function, it is important that the return movement or the backward stroke of the concentrator should 90 be quick, while the forward stroke should be slower. By virtue of this construction, the proper character of vibration is given to the concentrator for the separation of the metallic values from the gangue, and causing the 95 concentrates to travel continuously forwardly or toward the concentrates' discharge end of the table being that remote from the head motion.

The holder 26 carrying the bearing for the 100 rear extremity of the toggle 23, is engaged in the rear by cap screws C which are threaded in the part 12 and bear against the rear extremity of the device 26.

The necessity for the accuracy of the adjustment heretofore referred to, in head motions for concentrating tables, is due to the fact that these tables must be used to treat a great variety of ores in which different metals predominate. Owing to the fact that the 110 different metal values as well as the different varieties of gangue, have different specific gravities, it is essential that the head motion be differently adjusted for every variety of ore under treatment. Hence the necessity for 115 the various adjustments heretofore explained, that is to say the adjustments of the toggle members for imparting a quick return or rearward movement to the concentrator, while the spring imparts a more slow forward movement thereto. It is very important that the mechanism be so arranged that the toggle members be utilized to impart the return or rearward movement and the spring the forward movement. It is found in actual practice that where it is attempted to utilize a spring to impart a sufficiently quick return movement, a spring of such strength is required that it becomes impracticable to operate the mechanism in this way.

Having thus described my invention, what I claim is:

1. In mechanism of the class described, the combination with a concentrating table mounted to have a reciprocating movement, of a crank shaft, a hanger connected with the crank of the shaft, toggle members engaging the hanger, vertically adjustable toggle seats for the outer extremities of both toggle members, a lever upon one arm of which one of said seats is mounted, a vertically adjustable connection between the other arm of the lever and the concentrating table, and a spring actuating device engaging a vertical series of recesses formed in the lower arm, to act on said lever to move the said table in one direction, the toggle members being utilized to move it in the opposite direction, substantially as described.
2. In a head motion for concentrators, the combination with a concentrator and a suitable frame work, of a crank shaft journaled in the frame work, a hanger mounted on the crank pin of said shaft, a lever fulcrumed in the frame work, a toggle member having its opposite extremities seated in the hanger and the lower arm of the lever, respectively, a second toggle member, a vertically adjustable seat for the opposite extremity of the second toggle member, suitable means for connecting the upper arm of the said lever with the concentrator, and a spring-actuated device engaging the lower arm of the lever for imparting the forward movement to the concentrator, and means for changing the point of engagement of the said device with the lever arm, for the purpose set forth.
3. In a head motion for concentrators, the combination with a concentrator and a head motion frame work, of a crank shaft, a hanger connected to be actuated by the crank of said shaft, a lever fulcrumed on the frame work, a toggle member interposed between the said hanger and the lower arm of the said lever, a second toggle member having one extremity engaging the hanger on the opposite side from the first toggle member, a toggle seat for the opposite extremity of the second toggle member, means for the vertical adjustment of the toggle member extremities remote from the hanger, a vertically adjustable connection between the upper arm of the said lever and the concentrator, and a spring-actuated device for engaging the lower arm of the lever on the opposite side

from the first toggle member, the lower arm of the lever being provided with a vertical series of recesses, adapted to receive the spring-actuated device for the purpose set forth.

4. In a head motion for concentrators, the combination with a head motion frame work, of a crank shaft journaled in the frame work, a hanger connected to be actuated by said shaft, a lever fulcrumed in the frame work, a toggle member interposed between the hanger and the lower arm of said lever, a second toggle member interposed between the stationary part of the frame work and the hanger on the opposite side from the first toggle member, the upper arm of the said lever being provided with a vertical slot, a pin passing through said slot and vertically adjustable therein, a rod connecting said pin with the concentrator, the concentrator end of the rod being vertically adjustable to harmonize with the adjustment of the said pin, and a spring-actuated device engaging a vertical series of recesses arranged in the lower arm of the lever on the opposite side from the first named toggle member, substantially as described.

5. The combination with a structure to be vibrated, of a head motion therefor comprising a suitable frame work, a crank shaft journaled in the frame work, a hanger actuated thereby, a lever fulcrumed in the frame work, toggle members engaging the hanger on opposite sides, one of the said members engaging the lower arm of the lever while the other member engages the frame work, a vertically adjustable connection between the upper extremity of the said lever and the device to be vibrated, a cross bar, rods connecting the opposite extremities of the cross bar with the frame, a coil spring having one extremity engaging the cross bar intermediate its extremities, a seat for the opposite extremity of the said spring, the said seat having a rearward projection adapted to engage the lower arm of the lever which is provided with a vertical series of recesses therefor, substantially as described.

In testimony whereof I affix my signature in presence of two witnesses.

SAMUEL H. BOYLAN.
